DESIGN FOR A SHOE BUCKLE

Bennett W. Jayne, New York, N. Y.

Application October 29, 1935, Serial No. 59,258

Term of patent 3½ years

To all whom it may concern:

Be it known that I, Bennett W. Jayne, a citizen of the United States of America, residing in Manhattan, city of New York, county of New York, and State of New York, have invented a new, original, and ornamental Design for a Shoe Buckle, of which the following is a specification, reference being had to the accompanying drawing, forming part thereof.

I claim:

The ornamental design for a shoe buckle, substantially as shown.

BENNETT W. JAYNE.
